UNITED STATES PATENT OFFICE.

JOHN A. BODKIN, OF NEW YORK, N. Y.

INSULATED RAIL-JOINT.

1,057,406.

Specification of Letters Patent. Patented Apr. 1, 1913.

Application filed November 6, 1911. Serial No. 658,726.

To all whom it may concern:

Be it known that I, JOHN A. BODKIN, a citizen of the United States, residing at New York city, county of New York, State of New York, have invented a certain new and useful Improvement in Insulated Rail-Joints, and declare the following to be a full, clear, and exact description of the same, such as will enable others skilled in the art to which it pertains to make and use the same, reference being had to the accompanying drawings, which form a part of this specification.

My invention has for its object to produce a simple, rigid and durable joint for mechanically connecting together the ends of rails while insulating the rails from each other.

The various features of novelty whereby my invention is characterized will be herein-after pointed out with particularity in the claims, but for a full understanding of my invention and of its object and advantages, reference may be had to the following detailed description taken in connection with the accompanying drawings, wherein:

Figure 1 is a side view of two meeting rail ends secured together with my improved joint; Fig. 2 is a horizontal section taken directly beneath the heads of the rails, parts being broken away to show the manner of insulating certain of the bolts; Fig. 3 is an end view looking toward the right in Fig. 1, the rail being shown in section; Fig. 4 is an end view looking toward the left in Fig. 1, the rail being in section; and Fig. 5 is a perspective view of one of the joint members.

Referring to the drawings, 1 and 2 represent two adjacent rail ends which it is desired to fasten together mechanically while insulating them from each other electrically. In accordance with my invention, the joint itself, aside from the insulation and the bolts, consists of three pieces, preferably castings. The first of these pieces comprises a base plate 3 above one end of which lie two splice bar members 4 and 5. The members 4 and 5 preferably extend

from one end of the base plate to the middle where they terminate in laterally extending flanges 6 and 7. The members 4 and 5 form with the base plate a shell-like member for receiving one of the rail ends, the rail end being slipped between the two splice bar members until it comes flush with the flanges 6 and 7. The members 4 and 5 fit in the usual way between the head and the base flange of the rail, while room is left between the base plate and the underside of the base of the rail for a slab of insulating material 8. The members 4 and 5 are secured to the rail by the usual bolts 9 and 10 which pass through these members and the web of the rail. It will thus be seen that there is metallic contact between the rail 1 and the splice bar members 4 and 5, while the base is supported from beneath on a slab of insulating material which rests upon a rigid foundation. The free end of the base plate 3 underlies the second rail end, 2; the slab of insulating material 8 preferably extending throughout the length of the base plate so that both rails rest upon an insulating material. Half length splice bars 11 and 12 engage directly with and are secured to the rail 2 by means of any usual fastening such as the usual bolts 13 and 14, similar to the bolts 9 and 10. The ends of the splice bar members 11 and 12 adjacent to the end of the rail with which they are associated are provided with laterally projecting flanges 15 and 16 similar to the flanges 6 and 7. Between the flanges 6, 7 and the flanges 15, 16 is placed a post of insulating material 17, this post preferably extending completely across the joint and taking the configuration of the outer edges of the flanges. The two sets of flanges are rigidly secured together by means of bolts 18 and 19 extending through the flanges parallel with the longitudinal axis of the rails. The bolts are insulated, preferably from both flanges by means of insulating bushings 20 which surround them, and insulating washers 21 which overlie the outer faces of the flanges. The splice bar mem-

bers 11 and 12 are provided with laterally extending foot flanges 22 and 23 which overlie the portion of the base plate which projects outwardly beyond the sides of the rails, but do not come in contact with the base plate; thus providing an air gap between the members 11 and 12 and making room for the insulating slab 8, if it be desired to make the slab wide enough for this purpose. The flanges 22 and 23 are secured to the base plate by means of vertical bolts 24 and 25 which are insulated either from the base plate or from the flanges, preferably the latter. In the arrangement shown the base plate is provided with elliptical openings 26 through which the bolts 24 and 25 are adapted to pass, the bolts having oval necks, as indicated at 25^a in Fig. 1, which extend into these openings and prevent the bolts from turning when the nuts are screwed on. The openings 27 in the foot flanges of the splice bar members 11 and 12 may take any desired shape, being made larger than the bolts so as to permit insulating bushings to be placed around the bolts. The insulation of the bolts from the foot flanges is then completed by means of insulating washers 29 placed on top of the foot flanges. Wherever there is an insulating washer it may be protected by an overlying metal washer as indicated at 29^a in Fig. 1.

The base plate may be strengthened by a downwardly projecting rib or truss 30, that in the arrangement shown comprises a single member arranged midway between the ends of the base plate and along the longitudinal center thereof, so as to reinforce the base plate directly at the juncture of the rails.

It will thus be seen that I have provided an insulating joint in which there is no insulation between the rails and the members which are bolted thereto, the only insulation being between the rail ends, between the base plate and the bases of the rails and around the bolts which fasten the members of the joint to each other. Furthermore, the rigid base plate which is integral with the splice bar members engaging with one of the rails, gives a very secure support for both rails in the vertical direction, the stiffness of the base plate being increased by the truss on the underside thereof. The bolts which fasten the flanges of the splice bars together and which fasten the separable splice bars to the base plate are arranged at considerable distances from the longitudinal axis of the rail so that the bolts all have a long leverage and exert a powerful resistance against distortion or displacement of one rail relative to the other.

I claim:

1. In combination, two meeting rail ends,

a base plate underlying both of said rail ends, splice bars integral with one end of the base plate and engaging with one of the rails, splice bars detachably connected to the other end of the base plate and connected with the other rail, the meeting ends of said splice bars being provided with laterally projecting flanges, and means for securing said flanges together.

2. A connecting device for railway rails comprising a base plate having at one end integral half length splice bars, detachable half length splice bars connected to the other end of the base plate, said splice bars having laterally projecting flanges, and means for connecting said flanges together.

3. As an article of manufacture, a rail joint member comprising a base plate having integral splice bars extending from one end of the base plate to the center, said splice bars being provided with outwardly projecting flanges at their inner ends.

4. As an article of manufacture, a rail joint member comprising a base plate having integral splice bars extending from one end of the base plate to the center, said splice bars being provided with outwardly projecting flanges at their inner ends, and a truss extending downwardly from said base plate.

5. As an article of manufacture, a rail joint member comprising a base plate having integral splice bars extending from one end of the base plate to the center, said splice bars being provided with outwardly projecting flanges at their inner ends, and an integral truss extending downwardly from the base plate along the center thereof.

6. As an article of manufacture, a base plate having integral half length splice bar members extending from the center toward one end and laterally projecting flanges connecting the inner ends of the splice bar members with the base plate.

7. In combination, two meeting rail ends, a base plate underlying both of said rail ends, half length splice bars formed integral with one end of the base plate and engaging with one of said rail ends, half length splice bars engaging with the other rail end, the latter splice bars having foot flanges extending outwardly and lying at some distance above the base plate, bolts connecting said foot flanges to said base plate, bolts connecting the splice bars to the rails, said splice bars having laterally projecting flanges at their meeting ends, and means for connecting the latter flanges together.

8. In combination, two meeting rail ends, a base plate underlying both of said rail ends, a slab of insulating material interposed between said base plate and the bases of the rails, said base plate having integral

splice bars at one end thereof, means for securing the aforesaid splice bars to the corresponding rail end, detachable splice bars connected to the other rail end, insulated connections between the latter splice bars and said base plate, an insulating post between said rail ends, and insulated connections between the two sets of splice bars.

In testimony whereof, I, sign this specification in the presence of two witnesses.

JOHN A. BODKIN.
